UNITED STATES PATENT OFFICE.

SOLLO MENDELSON, OF LOS ANGELES, CALIFORNIA.

PICKPOCKET-PROOF POCKET-RECEPACLE.

SPECIFICATION forming part of Letters Patent No. 379,319, dated March 13, 1888.

Application filed January 9, 1888. Serial No. 260,267. (No model.)

To all whom it may concern:

Be it known that I, SOLLO MENDELSON, a citizen of the United States, residing at Los Angeles, in the county of Los Angeles and 5 State of California, have invented a new and useful Pickpocket-Proof Pocket-Receptacle, of which the following is a specification.

The object of my invention is to provide means for securing valuables in vest and similar pockets.

The drawings illustrate my invention.

Figure 1 is a view of the receptacle as it appears when secured in the pocket. A portion of the plate or casing A is broken away to expose the mechanism of the lock. Fig. 2 is a cross-section of the same on line $\alpha\alpha$, showing the receptacle closed to secure a watch in the pocket. Fig. 3 is a cross-section on the same line, showing the receptacle open to release the 20 watch. Fig. 4 shows the receptacle with the bolts pressed in to allow the receptacle to be placed in or removed from the pocket.

A A' are two metal plates, secured together near the lower side by hinges B B', mounted 25 on each side of the plates, so as to allow the top and bottom of the plates to be moved to and from each other, thereby allowing the mouth of the receptacle to be opened and closed. A flexible partition, C, is attached to 30 and extends between the plates A A' near their lower edges, to sustain the watch, and a spring, D, is mounted between the plates below the partition C. The tendency of the spring D is to hold the lower edges of the plates A A' 35 apart, thus closing the mouth of the receptacle, as shown in Fig. 2.

The device is equal in width to the width of the pocket in which it is designed to be placed, and is provided with two bolts, E E', which 40 project from either side thereof, as shown in Fig. 1. These bolts are mounted in ways F F' F'', provided therefor, and in which they slide to and fro. A spring, G, is mounted between these bolts and engages with them to 45 hold them apart, as shown in Fig. 1.

H H' are lugs or handles formed by bending the bolts E E' back upon themselves, providing means whereby the bolts can be pressed together, thus drawing them into the ways 50 F F'.

The operation of the device is as follows: The receptacle is placed in the vest-pocket by pressing the bolts together, as shown in Fig. 4, thus allowing the bolts to pass below the hem

at the mouth of the pocket. The bolts are 55 then released and passed through the lining of the pocket below the hem. This will prevent the receptacle from being drawn out of the pocket unless the bolts are first pressed together. The watch is then placed within the 60 receptacle, the tops of the plates A A' being first spread apart. This may be done by pressing the bottoms of the plates toward each other. Each plate is provided on its inner side with a hollow or depression, I, in which 65 the watch rests when the receptacle is closed. The shoulders J J' serve to retain the watch in the receptacle when the same is closed. When the watch is thus secured in the pocket, it cannot be removed without first opening the 70 receptacle. The one wearing the vest can easily do this by either pressing the bottoms of the plates toward each other or by pushing the tops of the plates apart, but it cannot be done by others without attracting attention. 75

The watch cannot be cut out of the pocket, as the receptacle is of metal.

The plates may be lined on the inside with chamois-skin, if desired.

Now, having described my invention, what 8c I claim as new, and desire to secure by Letters Patent, is—

1. The combination of the plates A A', hinged to each other near their lower sides, the springs D, mounted between the plates at 85 their lower sides, and the bolts E E', mounted in suitable ways, F F', and extending beyond the edges of the receptacle.

2. The pocket-receptacle set forth, comprising the combination of two metal plates 90 provided with inwardly-projecting shoulders at their upper sides and hinged together near their lower sides, the spring D, and the laterally-projecting movable bolts E E'.

3. The combination of the two metal plates 95 A A', hinged together near their lower sides, the spring D, mounted between the plates at their lower edges, the bolts E E' mounted in the ways F F' F'', and the spring G.

4. The combination of the plates A A', 100 hinged together near their lower sides, the spring D, flexible partition C, bolts E E', provided with the handles H H', mounted in the ways F F' F'', and the spring G.

SOLLO MENDELSON.
